UNITED STATES PATENT OFFICE.

CHANCY F. HEATH, OF GRAND RAPIDS, MICHIGAN.

BEDCLOTHES SUPPORT.

Application filed March 2, 1925. Serial No. 12,674.

To all whom it may concern:

Be it known that I, CHANCY F. HEATH, a citizen of the United States, residing at Grand Rapids, in the county of Kent and State of Michigan, have invented certain new and useful Improvements in Bedclothes Supports, of which the following is a specification.

My invention relates to improvements in appliances for attaching to bedsteads for holding the bed clothes in place after the bed has been made up, and its objects are: first, to provide a means whereby the foot end of the bed clothes may be held so firmly in place that the danger of drawing the ends of the bedclothes upwardly on the bed is fully eliminated; second, to provide a means whereby the clothes supporting elements may be readily applied to, and as readily removed from the bed, and, third, to provide a means whereby the locking elements that are designed to hold the clothes in place, may be wholly contained in the attachment I have produced instead of being detached therefrom and attached, in an unsightly manner, and position on the bed posts.

I attain these objects by the mechanism and construction of parts shown in the accompanying drawing, in which Fig. 1 is an elevation of a part of the foot posts and panel of a bedstead with my device, in its simpler form, in place. Fig. 2 is an edge elevation of the same. Fig. 3 is an edge elevation of one of my modified forms of supports with the clamping spring in place. Fig. 4 is a side elevation of the same. Fig. 5 is an edge elevation of another form of supporting bracket with the clamping spring removed. Fig. 6 is a back elevation of the clamping blocks showing the relative positions of the two blocks. Fig. 7 is an end view of the clamping blocks and the clamping spring showing the manner of clamping the ends of the bed clothes in place, and, Fig. 8 is a plan of the end rail of the bed showing the manner of securing the clamping spring to the rail when used in its simple form.

Similar reference characters indicate similar parts throughout the several views.

In the accompanying drawing 1 represents the bed posts; 2 2 are the side rails of the bedstead, 3 is the end rail and 15 is the panel at the foot of the bed.

My invention, in its simpler form, con-

sists of a spring metal supporting element 5—5' made into a U formed spring, the lower end of the part 5 being secured to the end rail 3 of the bedstead, by means of a clamp, *a*, secured in any available manner, as by the use of screws *d*. From this point the part 5' extends upwardly considerably above the upper edge of the clamping block 4 and has a locking element 6 65 pivotally secured thereto, as at *a*, there being two of these spring supports at the foot of the bed, as shown in Fig. 1. The clamping block 4 is formed with an offset *b* at the back, to provide a place for the reception of the auxiliary clamping block 7, the latter being preferably provided with serrated metal plates 13 for engaging, or being engaged by the locking elements 6 to force the auxiliary block solidly upon the fold of the 75 bed clothes 12 at the offset *b*, as indicated in Fig. 2. The clamping block 4 is securely connected with the part 5 of the clamping spring 5—5' by means of screws, as indicated at *c*. To secure the bed clothes 12 in 80 this clamping device I form a fold, as indicated at 12', in the end of the clothes, and pass the auxiliary block 7 between said folds, and pass the whole in the space between the vertical part of the clamping 85 block 4 and the surface of the clamping springs 5'. It will be readily understood that, with this construction, it is a simple matter to regulate the height of the supporting springs and blocks to correspond 90 with the height or thickness of the bed, by loosening the screws *d* so the part 5' of the spring may be slid upwardly or downwardly, as desired, and again securing the 95 clamping blocks 8 in place as before.

In Figs. 3, 4 and 5 I have shown modified forms of clamping spring supports at 9 and 14. The former is designed to be secured to the wooden end rail of the spring, by passing the hook or loop 9' over the edge of the rail, indicated by the dotted lines *e*, and that shown in Fig. 5 is designed to be secured to the upper surface of the spiral spring bed bottom by hooking the loop 14' 100 into the surface work of said springs, indicated by the dotted lines *f*. In both instances the upright standard of this support is slotted, as at 11, for the reception of a fastening bolt 10, by means of which the part 5 of the clamping spring is secured to the said upright, and can be adjusted upwardly or downwardly, as desired.

Returning to a description of the locking elements 6, the serrations 6' are designed to engage with the like serrations on the plate 13 to avert any possible danger of the auxiliary blocks becoming loosened and allowing the bed clothes to be drawn out of the clamp.

Having thus fully described my invention, what I claim as new in the art, is:

- 5 1. In a clamping device for holding bed clothes securely at the foot of the bed, U formed clamping springs having a long arm and a shorter arm, a clamping block secured to the shorter arm and having an offset in the back side thereof, an auxiliary clamping 15 block made to pass freely between the offset in the clamping block and the longer arms of the clamping springs, securing elements pivotally mounted upon the upper ends of the longer arms of the clamping springs in 20 position to be made to engage the upper surface of the auxiliary clamping block and hold it firmly in place, and means for securing the clamping device at the foot of the bed.
- 25 2. In combination with the elements covered in claim 1, serrated plates secured to the upper edge of the auxiliary clamping block, and serrations formed upon the free

ends of the securing elements in position to engage the serrations in the plates on the 30 edge of the auxiliary clamping block and hold the block securely in place.

3. In combination with the elements covered in claim 1, metal supporting brackets bent at right angles to form an upright arm 35 and a horizontal arm, the horizontal arm being bent at the end to form a loop that may be hooked into the surface structure of a bed spring, and the upright arm having a slot therein for the reception and free 40 movement of the bolt 10 longitudinally thereof, and a bolt passed therethrough and through the shorter arm of the clamping spring for properly securing and adjusting said clamping springs.

4. In combination with the elements covered in claim 1, serrated plates secured to the edge of the auxiliary block, the ends of the securing elements serrated to correspond with said plates, and brackets formed to 50 engage with the clamping springs and secure the same to the spring structure of the bed.

Signed at Grand Rapids, Michigan, February 14, 1925.

CHANCY F. HEATH.
